[57] CLAIM

The ornamental design for combined plural crayon unit and storage housing therefor, as shown and described.

DESCRIPTION

FIG. 1 is a perspective view of a combined plural crayon unit and storage housing therefor showing my new design;

FIG. 2 is a right side elevational view thereof;

FIG. 3 is a left side elevational view thereof;

FIG. 4 is a front elevational view thereof;

FIG. 5 is a rear elevational view thereof;

FIG. 6 is an end elevational view thereof;

FIG. 7 is an end elevational view of the end opposite that shown in FIG. 6; and

FIG. 8 is a perspective view thereof in an exploded condition.

FIG. 1

FIG. 2

FIG. 3

FIG. 4

FIG. 5

FIG.6

FIG.7

FIG. 8
